CLAIM

The ornamental design for a carrier for car care products, as shown and described.

DESCRIPTION

FIG. 1 is a top perspective view of a carrier for car care products, showing our new design;

FIG. 2 is a top plan view thereof;

FIG. 3 is a front elevational view thereof, the rear elevational view being a mirror image thereof;

FIG. 4 is a bottom plan view thereof; and,

FIG. 5 is a right side elevational view thereof, the left side being a mirror image thereof.

Fig.1.**Fig.2.****Fig.3.****Fig.4.****Fig.5.**
